LIQUID DISPENSER WITH A RESILIENT WALL PUMP

Leo W. Krall, Chicago Heights, Ill.

Application May 16, 1946, Serial No. 670,155

17 Claims. (Cl. 222—207)

1

This invention relates to fluid dispensers with a resilient wall pump, and more particularly to a combined closure and pump-type dispenser for liquid containers. Numerous devices of this character are on the market, but they have many objectionable features, such as outlets which readily clog, pumping mechanisms which are complicated and difficult to operate, and container air vents which readily leak or become clogged. This invention provides a combined dispenser and container closure which not only overcomes the disadvantages of known mechanisms, but also because of other improvements generally is more satisfactory and usable.

It, therefore, is an object of this invention to provide a dispenser with an outlet that is substantially clogproof when dispensing substances which do not flow readily and which solidify on drying, such e. g., as catsup.

It is another object of this invention to provide a pumping mechanism for a dispenser which is simple in construction and requires little effort on the part of the user to operate.

It is a further object of this invention to provide a dispenser with a simple air vent for the container which will not leak if the container is tilted or inverted, which at all times prevents the escape of vapors therefrom, and yet readily functions to admit air to the container to replace the dispensed contents.

Another object is to provide a positive closure for the discharge outlet which is permanently attached to the dispenser and is convenient to operate.

Still another object is to provide a dispenser in which the discharge outlet is not preformed, but may be conveniently opened by the user, thus allowing leakproof shipment of a container and its contents with the dispenser attached.

Other objects and advantages of the invention will appear in the following description and accompanying drawings, in which.

Figure 1 is a cross-sectional plan view of my dispenser taken on line 1—1 of Figure 2.

Figure 2 is a cross-sectional view in elevation taken on line 2—2 of Figure 1.

Figure 3 is a fragmentary cross-sectional view of a modified form of positive closure for the discharge outlet.

Figure 4 is a rear elevational view of the dispenser.

Figure 5 is a perspective view of the positive closure element of Figures 1, 2, and 4.

Figure 6 is a side elevation of a modified form of dispenser, partially broken away to show de-

2

tails of the means for forming the discharge outlet.

Referring now to Figure 2 of the drawings, there is shown a dispenser, indicated generally at 1, connected to a container 2 ready for use. An annular cap member 3 has lower interior threads 4 engaged with exterior threads 5 on the neck 6 of the container 2. Snugly mounted in the upper end of the cap member 3 is a compressible dome-shaped resilient bulb 7, preferably of rubber. The base of the bulb 7 has an annular exterior flange 8 seated in an annular interior groove 9 in the cap member 3. The flange 8 has an inclined upper edge cooperating with a correspondingly inclined edge of the groove 9 for more firmly retaining the bulb 7 in the groove 9. The walls of the bulb 7 are progressively thickened from its apex 10 to its base, to provide for greater flexibility. Because of this feature, less finger pressure is required on top of the bulb 7 to compress it inwardly, in order to dispense the contents of the container 2 as will be described later.

A short distance above the annular flange 8, at one side of the bulb 7, is a discharge aperture 11 formed in the wall of the bulb. An annular groove 12 may be formed in the inner wall of the bulb 7 around the aperture 11 to add flexibility to the wall of the bulb adjacent the aperture. An annular projecting rim or lip 13 may be formed on the exterior side of the aperture 11 to provide some stiffness to the walls of the aperture to prevent its possible collapse in use. Neither the annular groove 12 nor the projecting lip 13, however, are essential to the satisfactory operation of the dispenser. The upper portion of the cap member 3 is provided with an opening 14 aligned with the discharge aperture 11 to allow uninterrupted flow for the material discharged through the aperture. The diameter of the opening 14 in the cap 3 is greater than that of the annular projecting rim 13 of the aperture 11, in order to permit outward movement of the adjacent wall of the bulb 7 at this point, as will be described later.

The cap member 3 has an interior annular groove 15 in the plane of the opening 14 as best shown in Figure 1. A slot 16 in the cap 3, opens into the groove 15 at a point removed from the opening 14. The slot 16 is shown diametrically opposite the opening 14, but this is not essential. Rotatably mounted in the groove 15 is an arcuate closure member 17, best shown in Figure 5, having an operating tongue 18 which projects through the slot 16. The ends 19 and 20 of the

closure member 17, in its open position shown in Figure 1, lie on either side of the projecting rim 13 of the aperture 11. Clockwise rotation of the closure member 17 from the position shown in Figure 1, by means of the operating tongue 18, slides the end 19 over the discharge aperture 11, forming an effective seal with the projecting lip 13.

A partition member 21, best shown in Figure 2, has an annular flange 22 provided with a downwardly sloping upper surface which cooperates with a correspondingly sloping surface on the base of the bulb. These surfaces form a seal between the partition member 21 and the bulb 7 and serve to seat the bulb more firmly in the annular groove 9 in the cap member 3. The diameter of the flange 22 is somewhat less than the diameter of the groove 9, thereby forming an annular chamber 23. The partition member 21 has an upstanding annular wall 24 which forms an annular channel 25 between the wall 24 and the lower portion of the wall of the bulb 7. The annular channel 25 is interrupted by a projection 26 on the exterior of the wall 24 having a flat outer face for firmly seating against the wall of the bulb 7 surrounding the discharge aperture 11. Mounted in an annular groove 27 formed in the inner side of the base of the wall 24 is an arcuate member 28 supporting a flap valve 29. The valve 29 covers a central passageway 30 extending axially through the partition member 21. A tube 31 is engaged in the passageway 30 and depends into the fluid in the container 2.

From the construction thus far described, it may be seen that the bulb 7 and the partition member 21 define a chamber 32. Manual depression of the bulb 7 causes a pressure rise in the chamber 32 which urges the flap valve 29 into seated position over the passageway 30. At the same time, the pressure forces the wall of the bulb 7 surrounding the discharge aperture 11 slightly outward between the open ends 19 and 20 of the closure member 17 and into the opening 14 in the cap member 3. The outward movement of the wall unseals the inner end of the aperture 11 and fluid is forced therethrough.

The seal for the inner end of the discharge aperture 11 is shown as a projection 26 on the annular wall 24. The same result may be obtained by providing a projecting rim on the inner end of the aperture 11 and having it seat against the annular wall 24, in which event the projection 26 would not be required.

An important feature of my invention is the leakproof vent or air inlet means which allows air to be drawn into the container 2 to replace dispensed fluid. The partition member 21 has a centrally located, depending frusto-conical wall 33 surrounding the passageway 30. An annular depression 34 is formed between the frusto-conical wall 33 and the flange 22. Mounted in the groove 9 in the cap member 3 is an annular resilient sealing washer 35 adapted to be clamped between the flange 22 on the partition member 21 and the lip 36 surrounding the mouth of the container 2. When the dispenser 1 is attached to a container, the inwardly extending portion of the washer 35 covers the depression 34 and forms an annular chamber 36. The inner margin of the washer 35 acts as a check valve bearing against a seat formed by the depending frusto-conical wall 33 of the partition member 21. The under side of the annular flange 22 on the partition member 21 has a series of radial grooves 37 affording communication between the annular

chambers 23 and 36. The cap member 3 has an air vent opening 38 in communication with the chamber 23. In operation, the dispensing of fluid causes the pressure in the container to fall somewhat below atmospheric pressure, and air flows through the vent opening 38 into the annular chamber 23, through the grooves 37, and into the annular chamber 36, where the air unseats the inner margin of the washer 35 and enters the container 2.

A modified form of a positive closure for the dispensing outlet is shown in Figure 3. Threadably mounted in the opening 14 in the cap member 3 is an annular closure element 39, the inner end of which releasably bears against the wall of the bulb 7 surrounding the discharge aperture 11. After assembly of the closure element 39 with the cap member 3, the inner marginal edge of the closure element may be turned radially outward to provide an annular flange 40 for preventing complete withdrawal and consequent possible loss of the closure element. Screwing the closure element 39 inwardly causes its inner end to bear against the wall surrounding the aperture 11 and press the wall into sealing engagement with the projection 26, thus positively sealing the discharge aperture against leakage.

A modified form of dispenser outlet of this invention is shown in Figure 6. Here the closure member 17 has been omitted for simplicity of illustration. The annular wall 24 has a projection 41 which, instead of having a relatively large flat outer surface to seat against the inner end of an outlet aperture, tapers to a somewhat sharpened point. The projection 41 presses against the wall of the bulb 7 and pushes the wall slightly outward as shown. Before use, the wall has no pre-formed discharge aperture 11, as shown in Figure 6. The user of the dispenser 1 forms a discharge aperture in the wall of the bulb 7 by inserting a suitable pointed object, such as a wooden toothpick or the like, through the opening 14 and forcing it against the wall of the bulb, thus compressing the wall between the object and the projection 41 and punching an outlet or discharge aperture in the wall. Because the wall was stressed before the aperture was formed, the projection 41 will extend partially into the aperture to form a seal therefor. The operation of this type of outlet is otherwise similar to that described for the outlet shown in Figures 1 and 2. A pressure rise in the chamber 32 forces the wall of the bulb 7 surrounding the punched discharge aperture out of sealing engagement with the tapered end of the projection 41 to dispense fluid through the aperture. This modification of my invention is particularly desirable where the dispenser is used as a closure for a container during shipment. The lack of a prepunched discharge aperture results in less likelihood of leakage of the contents while the container is in transit. A further advantage is that after the aperture has been punched, the projection 41 extends slightly into the aperture and provides a spray type discharge during the dispensing operation.

The cap member 3 shown in Figure 6 also is slightly modified. The cap member has a pair of diametrically opposite upstanding ears 42 on either side of the opening 14. The ears 42 serve to protect the bulb 7 against accidental depression and discharge of the contents of the container.

The operation of the dispenser 1 is obvious from the above description. The cap member 3 is attached to a container with the tube 31 depending into the fluid to be dispensed. After opening

the closure member 17 or 39, the container 2 is grasped in one hand and the bulb 7 depressed by a finger. Depressing the bulb, for the initial use of the dispenser, causes a pressure rise in the chamber 32 closing the flap valve 29 and unsealing the discharge aperture 11, thus discharging air from the chamber. Release of the bulb 7 causes a negative pressure in the chamber 32 which combined with the resiliency of the wall about the discharge aperture 11 allows the inner end of the aperture to seat firmly against the projection 26, thus sealing the aperture. The negative pressure also opens the flap valve 29 and draws fluid from the container 2 through the tube 31 into the chamber 32. The withdrawal of fluid from the container 2 causes a negative pressure above the fluid therein, thus sucking air through the air vent opening 38, the annular chamber 23, the grooves 37, and the annular chamber 36, where the air unseats the inner margin of the washer 35, and passes into the container 2. Again depressing the bulb 7 dispenses the fluid in the chamber 32 through the aperture 11. The short length of the discharge aperture 11 allows very little, if any, residual remnants of the dispensed fluid to remain therein upon release of the bulb 7. This feature combined with the fact that there are no movable elements, such as ball check valves, in the discharge outlet, renders the outlet substantially clogproof. If the outlet should become clogged, it readily may be reopened by the insertion therein of a small pointed object such as a pin or the like. The air vent check valve formed by the washer 35 and the wall 33 not only is leakproof, but also prevents escape of the vapors of such volatile fluids, as perfumes. It will thus be seen that I have provided a simple yet improved and effective combined closure and dispenser.

While I have described specific forms of my invention, it will be realized that various changes and modifications in the specific form, construction, and arrangement of parts may be made without departing from the spirit of the invention. Accordingly, the scope of the invention is defined in the following claims.

I claim:

1. A fluid dispenser adapted to be applied to a container comprising: means defining a fluid receiving chamber for detachable connection to a container, said chamber being provided with a resilient wall, said wall having a first portion movable inwardly to reduce the size of said chamber and a second portion provided with a discharge aperture, sealing means for said aperture arranged interiorly of said chamber, said second wall portion being normally in engagement therewith, conduit means providing for passage of fluid from the container to said chamber, and a check valve positioned to control the passage of fluid through said conduit, said second wall portion being adapted to be moved outwardly from engagement with said sealing means to allow fluid to be discharged through said aperture when said first wall portion is moved inwardly of said chamber.

2. The structure set forth in claim 1 including an arcuate closure member for said discharge aperture, the said member being rotatably mounted about the second portion of the chamber wall.

3. The structure set forth in claim 1 including annular screw threaded means arranged exteriorly of the chamber about the aperture and adapted to releasably press the second flexible

wall portion into engagement with the sealing means.

4. A fluid dispenser adapted to be applied to a container opening comprising: means connectable to the container, resilient bulb means carried by said connectable means the said bulb means having a discharge aperture, partition means adapted to be positioned between said bulb means and the container opening and together with said bulb means defining a fluid receiving chamber, said partition means having a passageway for the flow of fluid from the container to said chamber, a check valve for controlling the flow of fluid through said passageway, and an upstanding portion of said partition means projecting into said chamber adjacent said discharge aperture, that portion of said bulb means surrounding said aperture being adapted normally to bear against said upstanding portion and seal said discharge aperture and to be forced away from said upstanding portion by pressure developed within said chamber to discharge fluid through said aperture.

5. In a fluid dispenser adapted to be applied to a container opening and having a dispensing outlet and pump means for drawing fluid from said container and dispensing it through said outlet, air vent means for the container comprising: a member adapted to be positioned over the container opening having a passageway therethrough for the flow of fluid from the container to the pump means, a downwardly and inwardly extending wall depending from said member, resilient sealing means interposed between said member and the lip surrounding the container opening and having an inwardly extending portion normally seating against said wall, and air inlet grooves formed between the outer margins of said sealing means and said member.

6. A fluid dispenser adapted to be applied to a container opening comprising: means connectable to the container, resilient bulb means carried by said connectable means, partition means adapted to be positioned between said bulb means and the container opening and together with said bulb means defining a fluid receiving chamber, said chamber being provided with a dispensing outlet, said partition means having a depending frustro-conical portion provided with a central passageway for flow of fluid from the container to said chamber, said portion being provided with radially extending outer marginal grooves in its lower surface, said connectable means having an air inlet opening in communication with said grooves, a check valve positioned to control the flow of fluid through said passageway, and resilient sealing means adapted to be interposed between said partition means and the lip surrounding the container opening, said sealing means having a central circular opening the annular margin of which normally seats against said frustro-conical portion and is adapted to be unseated in order to vent the container.

7. A fluid dispenser adapted to be applied to a container opening comprising: an annular sleeve element connectable to the container, dome-shaped resilient bulb means carried by said element and having a discharge aperture in a lower portion thereof, an annular resilient washer adapted to be positioned in sealing engagement with the lip surrounding the container opening, a partition member having an annular flange adapted to be received between the base of said bulb means and said washer and together with said bulb means defining a fluid receiving cham-

ber, said flange having radially extending marginal grooves formed in the lower surface thereof, said annular sleeve element having an air inlet opening in communication with said grooves, said member having an upstanding portion projecting into said chamber adjacent said discharge aperture, said lower portion of said bulb means about said aperture normally being in seating engagement with said upstanding portion and being adapted to be moved away therefrom by pressure developed in said chamber, said partition member also having a depending frusto-conical portion provided with a central passageway connected to a conduit, said conduit being adapted to depend into the fluid in the container, and a check valve positioned to control the flow of fluid through said conduit and said passageway into said chamber, the inner marginal portion of said washer normally being in seating engagement with said frusto-conical portion and being adapted to be unseated in order to vent the container.

8. A fluid dispenser adapted to be applied to a container comprising: means defining a fluid receiving chamber provided with a dome-shaped resilient wall, a lower portion of said wall having a discharge aperture, a closure member for said aperture substantially surrounding the base of said wall and rotatably mounted thereon for opening and closing said aperture, and conduit means providing for one way passage of fluid from the container to said chamber.

9. A fluid dispenser adapted to be applied to a container comprising: annular means connectable to the container having an interior annular groove and an opening through a side thereof in communication with said groove, dome-shaped resilient bulb means carried by said annular means having a discharge aperture in a lower portion thereof aligned with said opening, and an arcuate closure member mounted in said groove and adapted to be rotated into position to cover and to uncover said discharge aperture.

10. The structure set forth in claim 9 including a radially extending operating tongue on the closure member projecting through an opening formed in the annular means at a point spaced from said first mentioned opening.

11. A fluid dispenser adapted to be applied to a container comprising: annular means connectable to the container and having an opening through the wall thereof, resilient bulb means carried by said annular means having a discharge aperture aligned with said opening, sealing means for said aperture arranged interiorly of said bulb means, and an annular closure member threadably engaged in said opening, the inner end of said closure member being adapted to releasably press the wall of said bulb means about said aperture into engagement with said sealing means.

12. A fluid dispenser adapted to be applied to a container comprising: means defining a fluid receiving chamber provided with a resilient wall, said wall having a first portion movable inwardly to reduce the size of said chamber and a second portion adapted to be moved outwardly upon inward movement of said first portion, means arranged inwardly of said second portion having a projection against which said second portion normally bears, said projection being adapted to pierce said second portion and form a discharge aperture upon forcing said second portion thereagainst, and conduit means providing for one way passage of fluid from the container to said chamber.

13. A fluid dispenser adapted to be applied to

the mouth of a container as a closure therefor comprising: means defining a fluid trap chamber adapted for detachable connection to the container mouth, a portion of the wall of said chamber being resilient, movable outwardly, and provided with a discharge aperture; means within said chamber defining a sealing surface for the inner end of said aperture, at least the marginal portions of said wall portion about said aperture being normally in sealing engagement with said surface; means defining a passageway providing communication between said chamber and the interior of the container; a check valve associated with said passageway and operable to admit fluid into said chamber from the container, whereby upon development of fluid pressure within said chamber said marginal portions of said resilient wall portion are forced outwardly of said sealing surface to unseal said aperture and permit discharge of fluid therethrough.

14. A fluid dispenser adapted to be applied to the mouth of a container as a closure therefor comprising: means defining a fluid trap chamber adapted for detachable connection to the container mouth, a portion of the wall of said chamber being resilient, movable outwardly, and provided with a discharge aperture; means within said chamber defining a sealing surface for the inner end of said aperture, at least the marginal portions of said wall portion about said aperture being normally in sealing engagement with said surface; means defining a passageway providing communication between said chamber and the interior of the container; a check valve associated with said passageway and operable to admit fluid into said chamber from the container, whereby upon development of fluid pressure within said chamber said marginal portions of said resilient wall portion are forced outwardly of said sealing surface to unseal said aperture and permit discharge of fluid therethrough; and means associated with the container—connectable portion of said chamber-defining means for venting the container to the atmosphere to replace, with air, fluid dispensed therefrom.

15. A fluid dispenser adapted to be applied to the mouth of a container comprising: means defining a fluid trap chamber adapted for detachable connection to the container mouth, said chamber being provided with a dome-shaped resilient wall portion which is movable inwardly and a second resilient wall portion having a discharge aperture therethrough, said apertured wall portion being movable outwardly; means within said chamber defining a sealing surface for the inner end of said aperture, at least the marginal portions of the apertured resilient wall portion about said aperture being normally in sealing engagement with said surface; means defining a passageway providing communication between said chamber and the interior of the container; and a check valve associated with said passageway and operable to admit fluid into said chamber from the container, whereby fluid pressure within said chamber, developed by inward movement of said dome-shaped wall portion, forces said marginal portions of said apertured wall portion outwardly of said sealing surface to unseal said aperture and permit discharge of fluid therethrough.

16. A fluid dispenser adapted to be applied to the mouth of a container comprising: an outwardly directed substantially annular collar connectable to the container and provided with a

side opening therethrough; dome-shaped resilient bulb means carried by said collar and having a depending substantially annular portion fitting within said collar, said annular portion having a discharge aperture therethrough substantially aligned with and smaller than said collar opening; partition means closing said bulb means and together therewith defining a fluid trap chamber, said partition means having a passageway therethrough providing communication between said chamber and the interior of the container; a check valve associated with said passageway and operable to admit fluid into said chamber from the container; and means within said chamber defining a sealing surface for the inner end of said aperture, the marginal portions of the annular portion of said bulb means surrounding said aperture being normally in sealing engagement with said sealing surface and adapted to be forced outwardly therefrom by pressure developed within said chamber to permit the discharge of fluid through said aperture.

17. In a fluid dispenser adapted to be applied to the mouth of a container and having a fluid trap chamber, the combination of: an exterior wall and an interior wall mounted in opposition with portions of their opposed inner faces normally in contact, one of said walls being resilient

and the contacting portion of said exterior wall having an aperture therethrough for discharge of fluid from the chamber, the inner end of said aperture being sealed by the contacting portion of said interior wall, the inner face of said resilient wall having a portion thereof immediately adjacent said contacting wall portions exposed to fluid in the chamber; and means for developing fluid pressure in the chamber and thereby against said exposed resilient wall portion to force said contacting portion of said resilient wall out of contact with the contacting portion of the other said wall, to thereby unseal said aperture and permit discharge of fluid therethrough from the chamber.
